UNITED STATES PATENT OFFICE.

OLIVER SMITH, OF SULLY, IOWA.

MARKING ATTACHMENT FOR CORN-PLANTERS.

No. 895,507.

Specification of Letters Patent.

Patented Aug. 11, 1908.

Application filed April 13, 1908. Serial No. 426,766.

To all whom it may concern:

Be it known that I, OLIVER SMITH, a citizen of the United States, residing at Sully, in the county of Jasper, State of Iowa, have 5 invented certain new and useful Improvements in Marking Attachments for Corn-Planters; and I do hereby declare the following to be a full, clear, and exact description of the invention, such as will enable others 10 skilled in the art to which it appertains to make and use the same.

The present invention relates to improvements in marking attachments for corn planters, and it has for its primary object the 15 provision of an extremely simple and effective device of that nature which may be readily attached to the frame of a corn-planter of any ordinary type, may be swung to either side of the machine by means of a foot 20 lever, thus leaving the hands of the driver free, and which will be positively guided and held against displacement during its swinging movements.

More especially, the invention resides in 25 the specific construction of the staff of the marker, in the particular manner in which the marker is mounted with reference to the frame of the machine, and to the guides carried thereby, in the particular mechanism 30 employed for effecting the swinging movement of the marker, and in the particular manner in which the latter is connected with such mechanism.

The preferred embodiment of the invention 35 is illustrated in the accompanying drawings, in which corresponding parts or features, as the case may be, are designated by the same reference numerals throughout the several views, wherein:

40 Figure 1 is a plan view of the complete invention, showing the marker lowered. Figs. 2 and 3 are respectively, transverse and longitudinal sections taken on the lines 2—2 and 3—3 of Fig. 1. Figs. 4 and 5 are detail views, 45 respectively, of the marker and of the crank lever by which it is operated. Fig. 6 is a side elevation of the invention, showing the marker in upright position. Fig. 7 is an enlarged detail view of the bracket in which the 50 lever and drive shaft are journaled.

Referring more particularly to the drawings, 5 designates the frame of the corn planter, which latter may be of any ordinary type now in use, the longitudinal sills of said 55 frame being provided intermediate their ends with bracket bearings in which the axle

6 which carries the ground wheels 7 is journaled. Towards their front ends, the frame sills are connected together by a cross-beam 8, and at their rear ends by a pair of parallel 60 cross-beams 9 and 10 arranged in spaced relation to each other, the portions of each sill between the last mentioned beams and directly in front of the beam 9 being bent 65 downwardly to form the seats 11 shown in Figs. 3 and 6.

Upon each of the beams 9 and 10 is mounted an upstanding metal arch 12, which, in consequence of the above-described arrangement of said beams, are likewise disposed in 70 spaced relation to and parallel with each other. The rear beam 10 has set into its inner side face, intermediate the ends thereof, a horizontal pin 13 to which the marker rod 14 is pivoted at its inner end, said rod carrying 75 at its outer end a revoluble marking disk 15. The marker, as a whole, is thus capable of a swinging movement in a vertical plane between the arches 12, which thus not only 80 serve to guide the marker during such movements, but also to hold it against lateral displacement, the movement of the marker in either direction being limited by its contact with the corresponding seat 11, the height of the beam 10 and the depth of the seats being 85 sufficient to permit the marking disk to contact with the ground when the marker rod rests in either seat, as will be understood.

Intermediate its ends, the marker rod is 90 provided with a slot 16 through which projects a laterally-extending crank-finger 17 formed on the outer end of a lever 18, whose inner end is provided with a similar crank-finger 19 which, however, extends in the opposite direction from the finger 17 and projects 95 through the lower of a pair of horizontal openings 20 and 21 formed in an upstanding bracket 22, mounted upon the beam 9, the fingers 17 and 19 being held against displacement from the slot 16 and opening 21, 100 respectively, by any preferred devices.

The finger 19 has rigidly secured thereto a gear 23, which meshes with a larger gear 24 carried by a shaft 25 which is disposed longitudinally of the frame of the machine and 105 has its rear end projecting through the upper opening 20 in the bracket 22, while its front end is journaled in a bracket bearing secured to a cross beam 26 whose ends are fastened to the side sills of the frame, the extreme rear 110 end of said shaft having secured thereto a treadle 27. The treadle is arranged for opera-

tion by the feet of the occupant of the seat 28, the seat supporting strap being likewise secured to the cross beam 26.

The arrangement of the treadle with respect to its shaft is such that when said treadle occupies an approximately horizontal position, the marker extends directly upwards, or in other words, is disposed at right angles to the beam 10 to which it is pivoted. 10 When, therefore, either end of the treadle is depressed, the consequent rotation of the shaft 25 will be transmitted to the crank lever 18 through the gears 24 and 23, whereupon said lever, and with it the marker, will 15 be swung in a vertical plane, the direction of movement of the lever and marker being opposite to the direction of rotation of the shaft 25. Thus, when the right hand end of the treadle, with respect to Fig. 1, is depressed, the marker will be swung downwardly to the left and vice versa. It will thus be understood that the movements of the marker are controlled entirely by the treadle which is operated by foot pressure, 20 the hands of the operator being thus left free.

During the progress of the machine and while the marker is not in use, it may be retained in vertical position by pressure upon 30 both ends of the treadle.

What is claimed is:

1. In a machine of the class described, the combination, with a pivoted marker, of a lever disposed parallel with the marker and 35 provided at each end with a crank finger; one of said fingers being engaged with said marker; a gear secured to the other finger; a shaft disposed at right angles to said lever; a gear secured to said shaft in mesh with the 40 first-mentioned gear; and means for rotating said shaft in either direction, to swing said lever and said marker in a vertical plane.

2. In a machine of the class described, the combination, with a pivoted marker provided intermediate its ends with a slot; of a lever pivoted at one end and provided at its 45 other end with a crank finger engaged in the slot in the marker; a gear secured to the pivoted end of the lever; a shaft disposed at right angles to said lever; a gear secured to 50 said shaft in mesh with the first mentioned gear; and means for rotating said shaft in either direction, to swing said lever and said marker in a vertical plane.

55 3. In a machine of the class described, the

combination, with a pivoted marker provided intermediate its ends with a slot; of a lever pivoted at one end and provided at its other end with a crank finger engaged in the slot in the marker; a gear secured to the 60 pivoted end of the lever; a shaft disposed at right angles to said lever; a gear secured to one end of the shaft in mesh with the first-mentioned gear; and a treadle secured to the other end of said shaft, for rotating the 65 same in either direction, to swing said lever and said marker in a vertical plane.

4. In a machine of the class described, the combination, with a frame including parallel side sills, of a pair of spaced upstanding arches arranged transversely of the frame and having their ends secured to said sills; a marker pivoted at its inner end to the frame for movement in the space between said arches; a lever disposed parallel with 75 the marker and provided at each end with a crank finger; one of said fingers being engaged with said marker; a gear secured to the other finger; a shaft disposed at right angles to said lever; a gear secured to said 80 shaft in mesh with the first-mentioned gear; and means for rotating said shaft in either direction, to swing said lever and said marker in a vertical plane.

5. In a machine of the class described, the 85 combination, with a frame including parallel side sills, of a pair of spaced upstanding arches arranged transversely of the frame and having their ends secured to said sills; a marker pivoted at its inner end to the frame, for 90 movement in the space between said arches, said lever being provided intermediate its ends with a slot; a lever pivoted at one end and provided at its other end with a crank finger engaged in the slot in the marker; a gear secured to the pivoted end of the lever; a shaft disposed at right angles to said lever; a gear secured to one end of the shaft in 95 mesh with the first-mentioned gear; and a treadle secured to the other end of said shaft, 100 for rotating the same in either direction, to swing said lever and said marker in a vertical plane.

In testimony whereof, I affix my signature, in presence of two witnesses.
